Primary Examiner — Raphael Barkai*(74) Attorney, Agent, or Firm* — Nicole J. Einerson(57) **CLAIM**

The ornamental design for a headgear-earwear assembly, as shown and described.

DESCRIPTION

FIG. 1 is a perspective view of a new design for a headgear-earwear assembly;

FIG. 2 is a close-up perspective view thereof;

FIG. 3 is a close-up front elevational view thereof;

FIG. 4 is a close-up rear elevational view thereof;

FIG. 5 is a close-up top plan view thereof, the close-up bottom plan view being a mirror image of the top plan view;

FIG. 6 is a close-up left side perspective view thereof; and,

FIG. 7 is a close-up right side perspective view thereof.

In the drawings, the broken lines form no part of the claimed design.
